REFRIGERATED SELF-SERVICE DISPLAY CASE

Steven J. Toth, Kendallville, and Karl A. Emch, La Grange, Ind., assignors to Streater Industries, Inc., Albert Lea, Minn.

Filed Sept. 24, 1969, Ser. No. 19,292

Term of patent 14 years

Int. Cl. D15—10

U.S. Cl. D80—11

Fig. 1

FIG. 3

FIG. 1 is front perspective view of a refrigerated self-service display case showing our new design;

FIG. 2 is an end view thereof; and

FIG. 3 is a rear elevational view thereof, the center being broken away for convenience of illustration.

We claim:

The ornamental design for a refrigerated self-service display case, substantially as shown.
